UNITED STATES PATENT OFFICE

JOHN SCHADE, OF HOLYOKE, MASSACHUSETTS, ASSIGNOR TO NATIONAL BLANK BOOK CO., A VOLUNTARY TRUST ASSOCIATION OF COPARTNERSHIP, WITH F. B. TOWNE, E. S. TOWNE, J. M. TOWNE, AND F. W. WILSON AS TRUSTEES

VISIBLE-INDEX BOOK

Application filed April 5, 1928. Serial No. 267,515.

My invention relates to visible index books which comprise a plurality of sets of record slips or leaves removably held by binder posts in graded form with their lower edges 5 "feathered" so that a portion of the edge of each sheet will be disclosed and identified in any suitable manner so that they may be easily located, and between each of these sets is an interleaver whereby the sets are segregated.

The books which contain these sets or leaves are of the kind known as loose leaf binders and the slips of each set as well as the interleaving sheets are perforated along their 15 inner edges and through these perforations extend the posts of the binder, these posts being secured to the expandable sections of the back portion of the binder, so that when the book is opened and these telescoping sections 20 spread apart said posts will be likewise spread apart more or less as desired, whereby the slips may be readily thrown from one set of posts to the other or may be removed and suitable insertions made.

25 This invention is closely identified with the invention shown and described in my pending application, Serial No. 222,457, filed September 28, 1927, and the particular object of the present invention is to render the 30 pivoting of either of the two series of the leaf-carrying parts entirely unnecessary, and to so arrange these parts that they are rigid and are capable of being spread apart by two successive sliding movements, the first of 35 which follows the opening of the book and the spreading of the telescoping sections to place the binder in shape for the usual manipulation of the sheets from one side to the other with the parts always engaging within 40 the perforations in the sheets. The other or final sliding movement of the two series of posts, is brought about by extending the outward sliding movements of said sections to their limit so as to separate the ends of one 45 series of posts from the ends of the other series, leaving a space between said ends amply sufficient to permit of the ready withdrawal or insertion of sheets.

50 One series of posts is capable of lengthwise shifting movements so that additional sheets

may be placed at the top or bottom of a series of sheets, or a sheet inserted between two other sheets, this characteristic being fully shown and described in my aforesaid pending application, and therefore no novelty is 55 claimed for this feature.

In the accompanying drawings which form a part of this application

Figure 1 is a plan view of the inside of the book, with the interleavers and slips removed, 60 and showing the back sections closed and the parts in their normal condition.

Figure 2 is a section at the line 2—2 of Figure 1.

Figure 3 is a section at the line 3—3 of 65 Figure 1.

Figure 4 is a view similar to Figure 1 but showing the back sections initially spread, so that the sheets may be manipulated from one set of posts to the other set.

70 Figure 5 is a section at the line 5—5 of Figure 4.

Figure 6 is an inside view showing the sections spread to their limit and one set of posts shifted.

75 Figure 7 is a section at the line 7—7 of Figure 6.

Figure 8 is a section at the line 8—8 of Figure 1.

80 Figure 9 is a section at the line 9—9 of Figure 4, and

Figure 10 is a section at the line 10—10 of Figure 6.

85 Similar numerals of reference denote like parts in the several figures of the drawing.

The drawings do not show any record slips or interleavers in position on the posts, since the object of visible index books and the manner of manipulating such slips and interleavers are so well known that illustrations in these respects are deemed unnecessary.

90 1, 2, are telescoping metallic back sections, such as are common in loose leaf ledgers, and 3, 4, are the side covers which carry spaced hinge eyes 5, 6.

95 The sides 7, 8, of the sections 1, 2, are at right angles to the back portions and have at spaced intervals along their edges hinge eyes 9, 10, the hinge eyes of the covers and 100

these sides being alined and pintles 11, 12, passed through them whereby the covers are hinged to the sides.

The section 1 has rectangular ends 13 that 5 terminate in inturned flanges 14 which are disposed in telescoping relation beneath similar inturned flanges 15 at the ends 16 of the section 2.

17 is a shift bar whose lower edge has lugs 10 18 that track within elongated slots 19 in the back portion of the section 1, the upper edge of this bar having formed therewith at spaced intervals eyes 20 through which the pintle extends, and the portions of the latter embraced by the eyes are longer than said eyes, so that it will be clear that the bar 17 may be shifted lengthwise.

21 is one series of parallel posts secured to the bar 17 and extending toward the section 2 and in parallelism with the backs of the sections.

Confined within the side 8 of the section 2 by means of an elongated strip 22 is a slide 23, this strip being spaced from the side 8 to 25 provide a runway for the slide and having at its upper edge hinge eyes 24 alined with the eyes 6 and 10 and surrounding the pintle 12, the lower edge of this strip having inturned portion 25 that abuts the slide 23 to keep it in place. 21^a is a series of posts rigidly secured to the strip 22 and extending toward the posts 21 in parallelism and in spaced relation thereto. Elongated slots 27, 28, are formed in this slide 23, and through these 35 slots screws 29, 30, are driven from the strip 22 into the side 8, the object of this being to secure the strip to said side and to permit the free lengthwise movements of the slide 23, and at the same time to cause the portion 25 to stiffen the strip. The slide 23 has at 40 its lower edge flanges 31, 32, that extend inwardly parallel with the back of the section 2, and slightly spaced therefrom so as not to interfere with the back of the section 1 when the sections are telescoped in closed 45 position.

33, 34, are links whose extremities are respectively pivoted to the flanges 31, 32, and to the back of the section 1, so that it will be understood that when said sections are 50 spread these links will operate to throw the slide 23 outwardly thereby causing the flanges 31 and 32 to travel with said slide.

Pivoted at 35 to the upper corner of the 55 front end of the slide 23 is a bell-crank lever 36, whose outer end terminates in a finger grip 37, whereby the lever and consequently the slide may be pulled outwardly. The inner or lower crank portion of this lever 36 is connected to the slide 23 by means of a coiled spring 38 which functions to normally throw the main lever that carries the finger grip downwardly against the adjacent end 60 16, and a notch 39 is cut in the bottom edge 65 of this lever which notch engages the end

16 when the sections have been initially spread, as shown at Figure 5, and when it is desired to spread the sections to their limit the operator merely lifts the bell crank so as to disengage the notch and then by means of the finger grip pulls the slide outwardly to bring the parts into the position shown at Figures 6 and 7.

The normal position of the parts of the book is with the sections closed, as is shown at Figure 1, and the links 33 and 34 will be parallel with the sides 7, 8, and the slide 23, with its flanges 31, 32, will be at the extremity of its inward adjustment and the finger grip 37 will be against the end 16.

In order to place the book in condition for convenient manipulation of the slips and interleavers that are threaded on the posts, the operator, after opening the covers, grasps the sides 7, 8, and pulls them apart thereby causing the slide to be thrown outwardly until it is arrested by the engagement of the notch 39 with the end 16 of the section 2, and when the sections are in this position, as is shown at Figure 4, it will be observed that the ends of the posts are in overlapping relation with respect to each other so that the slips and interleavers may be readily manipulated from one side of the book to the other without danger of the perforations in such slips and interleavers leaving the posts. The sections of the book are closed by merely pressing them together.

Whenever it is desired to remove any slips from the book or to introduce additional slips, the operator, after spreading the sections to the position shown at Figure 4, lifts the protruding bell-crank and by means of the finger grip 37 pulls the lever 38 forwardly to its limit, thereby causing the links 33 and 34 to straighten out and to thus force the sections apart to their limit, as shown at Figure 6, and it will be observed that when the parts are in the condition shown at Figure 6 the posts will no longer be in overlapping relation, but will be separated so that the slips may easily be removed therefrom or introduced thereon.

In closing the book, after it has been brought into the position shown at Figure 6, it is merely necessary to thrust the bell-crank inwardly to its limit until the finger grip 37 abuts the end 16.

The links not only function to permit the proper spreading and contraction of the sections when the slide is operated but they also serve as a means to prevent the sections from spreading beyond the proper limit such as might cause their disengagement entirely.

The insertion of slips intermediate of other slips is very readily affected since it is merely necessary to bring the sections to the position shown at Figure 4, move all of the slips to the right onto the posts 21, shift the bar 17 with the post 21 and the slips, then part the

slips at the place where the insertion is to be made, throwing one of the parted portions to the left of the book, spread the sections fully to the position shown at Figure 6, then 5 insert the new slip in its proper place with its edge immediately above the top slip at the right of the book, shift back the bar 17 to its normal position and close the book.

In fact, this operation just described is common to all books of this description in which 10 a shift bar is utilized, the feature of this particular invention being that the posts have no pivotal relation with any part of the book, but are rigid straight structures which can be separated far enough to permit of the ready 15 removal or insertion of the sheets.

Having thus described my invention what I claim is:—

1. A visible index book, comprising sections whose backs and ends are disposed in 20 slidable relation, posts carried by the sides of said sections in normal parallelism with each other and with the backs of said sections, and means for automatically limiting the initial 25 spreading of said sections to partially open position, said means being manually operable to permit the spreading of the sections to their limit.

2. A visible index book, comprising a back 30 of telescoping sections, a series of straight leaf-carrying posts rigidly secured to one of said sections and a series of similar posts mounted on the other section so as to be shiftable lengthwise, both sets lying in parallelism 35 with the backs of the sections, and means carried by one section for automatically limiting the initial spreading of said sections to partially open position, said means being manually operable to permit the sections to be spread 40 to their limit.

3. A visible index book, comprising a back 45 of telescoping sections, a series of straight leaf-carrying posts rigidly secured to one section in parallelism with the back thereof, a bar carried by the other section and adapted 50 for limited longitudinal sliding movement, a series of straight leaf-carrying posts rigidly secured to said bar and extending toward the first-mentioned series of posts in parallelism 55 therewith and in staggered relation thereto, and means serving to limit the extension of said sections to definite successive stages.

4. A visible index book, comprising two 55 telescoping back sections, a series of leaf-carrying posts rigidly carried by one section in parallelism with the back thereof, a shift bar carried by the other section and confined except as to sliding movements, a series 60 of leaf-carrying posts rigidly secured to said bar and extending toward the first series of posts in parallelism therewith and in staggered relation thereto, means serving to limit the expansion of said sections to a definite stage with the ends of the posts of each 65 series in overlapping relation, and means

serving to limit the further expansion of said sections with the ends of the posts of one series spaced from the ends of the post of the other series.

5. A visible index book, comprising two telescoping back sections, a series of leaf-carrying posts rigidly carried by one section in parallelism with the back thereof, a shift bar carried by the other section and operable between prescribed limits, a series of leaf-carrying posts rigidly secured to said bar and extending toward the first series of posts in parallelism therewith and in staggered relation thereto, slidable elements within the first-named section and capable of movement lengthwise thereof, links pivotally connecting said elements with the other section, and a notched resilient bell-crank lever pivoted to one of said elements and adapted for automatic engagement with a stationary part to limit the initial spreading of the sections, said means being manually operable to release said engagement and thereby permit the full spread of said sections.

6. A book for visible indexes, comprising two telescoping sections, a series of straight parallel posts rigidly carried by each section in spaced relation and in a plane that is parallel to the backs of said sections, and means for automatically limiting the spreading of said sections to two definite stages.

7. A construction as in claim 6, further distinguished in that the first stage brings the ends of the posts of each series in overlapping relation whereby the sheets carried thereby may be manipulated from one side of the book to the other, while the second stage spaces the posts of one series from the posts of the series in the direction of their lengths, whereby sheets may be removed from or inserted on said posts.

In testimony whereof I affix my signature hereto.

JOHN SCHADE.
